ARC INTERRUPTER

Filed Sept. 12, 1930

FIG. 3.

FIG. 2.

FIG. 1.

Roy R. Pittman

INVENTOR

UNITED STATES PATENT OFFICE

RALPH R. PITTMAN, OF PINE BLUFF, ARKANSAS

ARC INTERRUPTER

Application filed September 12, 1930. Serial No. 481,437.

This invention relates to means for protecting electrical power and transmission lines and/or apparatus connected thereto by draining from the line and/or apparatus high superimposed voltages and their attendant currents, such as may be caused by lightning and particularly to a device of the general type shown in my copending applications Nos. 477,897, filed August 26, 1930, and 10 478,995, filed August 30, 1930. The object of my present invention is to provide a safety device for protecting against injury the fibrous insulating tube which forms the arcing chamber, while at the same time insuring a prompter action of the pressure gases in the arcing chamber during the operation of the interrupter.

Another object is the provision of a novel construction of an arc interrupter for use in connection with electrical transmission lines and/or apparatus connected thereto, and a further object is the provision of means for indicating after each operation the condition of the arcing chamber of the arc interrupter.

25 In the drawing:

Figure 1 is an elevation of a transmission line supporting tower with the arc interrupter arrangement mounted thereon in service position.

30 Figure 2 is an elevation of an arc interrupter as constructed in accordance with the invention.

Figure 3 is a vertical section through the interrupter.

35 The present construction possesses certain general features in common with those described in the applications above mentioned, and includes a fibrous insulating tube 18 grounded at 16 from a lower electrode 22. A

40 top electrode 21 is supported in place by a metal connecting plug 24 which entirely closes the opening of the tube, and is secured rigidly in place by a metal band 25. The metal band 25 entirely encircles the insulating tube 18 and is tightly clamped thereon, thus holding the plug 24 and electrode 21 rigidly in place. A weather-proof metal cap 19 is electrically connected by a fusible element 23 to the metal conducting plug 24. The fusible element 23 is attached by any suitable means,

not shown, to the metal cap 19 and metal plug 24. Soldering has been found a suitable means in case copper wire is used as the fusible element.

In the drawing, Figure 1 illustrates a tower 55 carrying three transmission line conductors 10 such as may be used in a three-phase transmission line.

In accordance with the usual practice, these conductors are suspended from suspension 60 insulators 11 depending from a wooden cross arm 12, which connects the tops of the tower poles 13, which poles are suitably anchored in the ground at their bases 14 and are provided throughout their entire lengths with ground 65 wires 15 which are well grounded as indicated at the points 16.

In vertically spaced relation below the transmission line conductors 10, the poles 13 are provided with a metal cross arm 17, which 70 is of metal construction throughout and which is secured to the poles in positive electrical contact with the ground wires 15.

On the metal cross arm 17 are detachably mounted at spaced intervals vertically below 75 the respective transmission line conductors, a series of arc interrupters 18, one of which is illustrated in detail in Figures 2 and 3, all of the interrupters being identical in construction.

80 In operation, any extraneous voltage superimposed on a conductor 10, which is of sufficient value will cause a current to flow from this conductor 10 to the weather-proof cap 19 through the fusible element 23 to the conducting plug 24; from the conducting plug 24 to the electrode 21 and thence to ground 85 16, through the fibrous insulating tube 18, the lower electrode 22 and the ground wire 15. In this manner, an arc is established from the conductor 10 to the weather-proof cap 19 and within the arc interrupter from the electrode 21 to the electrode 22. The distance within the fibrous insulating tube from the top electrode 21 to the lower electrode 22 is purposely 90 made less than is the distance from the weather-proof cap 19 to the lower electrode 22, and thus the discharge naturally follows the path inside the tube.

95 Immediately following the drainage of the 100

extraneous current caused by the superimposed voltage, dynamic arcs are established between the conductor 10 and/or its supporting clamp and weather-proof cap 19 and also 5 between the top electrode 21 and the lower electrode 22 within the fibrous insulating tube 18.

Before the usual circuit breakers with which transmission systems are provided 10 have had time to operate, the dynamic arc within the tube 18 will be extinguished due to the generation of gas by the action of the arc on the material of the insulating tube. Thus the interior of the tube rapidly fills with 15 gas which vents through the open lower end of the electrode 22, extinguishing and expelling the arc within the tube. By this arrangement it will be apparent that a means has been provided for draining off heavy 20 superimposed voltages and for immediately extinguishing the resulting arc so that there will be no interruption to service over the transmission lines.

Inasmuch as the extinguishment of the arc 25 is caused by the action of the arc on the material forming the inside walls of the arcing chamber through the generation of gas, it will be apparent that after successive operations the inner walls of the fibrous insulating tube 30 forming the arcing chamber will be eventually so affected by the high temperature of successive arcs as to cause a reduction in the quantity of gas generated and hence in the 35 velocity of its expulsion from the arcing chamber. When such a condition obtains, the dynamic current flow will continue for a sufficient length of time to destroy the fusible element 23, thus inserting in the circuit to ground an additional length of fibrous tube 40 and extinguishing the arc by this means. Since the metal conducting plug 24 is rigidly secured in place in the tube, the gas formed upon the fusing of the element 23 is of sufficient pressure to remove the weather-proof 45 cap 19, thus venting the gases formed in the upper portion of the arc interrupter and at the same time giving positive visual indication that the arc interrupter has been rendered unfit for further service as such.

50 Inasmuch as the temperature to which the fusible element 23 is subjected is a function of not only the magnitude of the current, but also of the length of time the said current flows through the fusible element, it will be 55 seen that the fusible element 23 will not be destroyed until the inside wall of the fibrous insulating tube 18 is so affected that the quantity and hence the velocity of the gases generated in that section of the tube between 60 the electrodes 21 and 22 will not quickly interrupt the flow of the current.

This arrangement also results in so locating the arcing chamber of the interrupter that the 65 gases generated therein travel the minimum distance before being vented, thus resulting

in prompter action in the extinguishing of the arc.

While in this preferred form I have illustrated and described certain details entering into the construction and operation of the invention, it is to be understood that the same do not constitute limitations but that any desired changes and modifications may be made in the structural details as fall within the scope of the invention as claimed.

I claim:

1. In an arc interrupter, the combination of a hollow tube of insulating material, a metal cap disposed over one end of said tube and forming an electrode, a metal plug rigidly secured to the tube at a considerable distance therein and entirely closing the opening of the tube, a fusible element connecting said cap with said plug, and a metal tube forming a third electrode in spaced relation to said plug within the tube.

2. In an arc interrupter, the combination of a hollow tube of fibrous insulating material, a metal cap disposed over one end of said tube and forming an electrode, a metal plug rigidly secured to the tube at a considerable distance therein and entirely closing the opening of the tube, a fusible element connecting said cap with said plug, and a third metal electrode in spaced relation to said plug within the tube.

3. In an arc interrupter, the combination of a hollow tube of insulating material, a removable metal cap disposed over one end of said tube and forming an electrode, a metal plug rigidly secured to the tube at a considerable distance therein and entirely closing the opening of the tube, a fusible element connecting said removable cap with said plug, and a metal tube forming a third electrode in spaced relation to said plug within the tube.

4. In an arc interrupter, the combination of an insulating tube of material adapted for volatilizing on the occurrence of an arc whereby to extinguish the arc and expel gases from the open end of the tube, a metal cap disposed over one end of said tube and forming an electrode, a metal plug rigidly secured to the tube at a considerable distance therein and entirely closing the opening of the tube, a fusible element connecting said cap with said plug, and a metal tube forming a third electrode in spaced relation to said plug within the tube.

5. In an arc interrupter, the combination of a hollow tube of fibrous insulating material, said material being adapted for volatilizing on the occurrence of an arc whereby to extinguish the arc and expel gases from the tube, a removable metal cap disposed over one end of said tube and forming an electrode, a metal plug rigidly secured a considerable distance within said tube and entirely closing the opening of the tube, a fusible element con-

necting said removable cap with said plug, and a grounded metal tube forming a third electrode in spaced relation to said plug within the tube.

- 5 6. In an arc interrupter, the combination of a hollow tube of insulating material, a metal electrode closing one end of the tube, a metal plug rigidly secured to the tube at a considerable distance therein and entirely 10 closing the opening of the tube, a fusible element connecting said electrode with said plug, and another electrode in spaced relation to said plug within the tube, there being material between said plug and the latter electrode 15 adapted for volatilizing upon exposure to an arc to extinguish the arc and expel gases from the open end of the tube.

In testimony whereof I affix my signature.
RALPH R. PITTMAN.
